RAIL RETAINING KEY

Application filed November 11, 1931. Serial No. 574,316.

Our invention relates to rail retaining keys and more particularly to a resilient key designed for use in combination with a rail and a special form of tie plate as a means for 5 either limiting or resisting vertical movement between the latter elements. In using the term "tie plate" herein, we mean to include any type of plate or foundation upon which the base of a rail is adapted to rest or 10 to be secured.

One object of the invention is to provide a retaining key which when used in combination with a particular form of tie plate will enable rails to be quickly and readily assembled upon the tie plates and to be removed 15 with equal facility. Another object of the invention is to provide rail retaining keys and tie plates which are of simple and inexpensive manufacture, and yet which, when 20 used in association with each other according to the practice of the invention effectively serve to limit or resist vertical movement of the rails to which they are applied. Still another object of the invention is to take advantage 25 of the inherent resiliency of a rail retaining key in causing the same to become locked or caught upon a tie plate in a manner such as to prevent dislodgment incident to service in track.

30 Further objects and advantages characteristic of our invention will become more apparent from the description hereinafter of an embodiment or example thereof, the description having reference to the accompanying drawing. Of the drawing:

Fig. I represents a plan view of a rail, a tie plate and retaining keys of our invention, the rail being in horizontal section to show the parts more clearly.

40 Fig. II represents a vertical cross-section of the same, taken as indicated by the lines II—II of Fig. I.

Fig. III represents a longitudinal section of a portion of the tie plate, taken as indicated by the lines III—III of Fig. I; and,

Fig. IV represents an enlarged bottom view of a portion of the tie plate, showing the manner in which a retaining key is locked therein.

There is shown in the drawing a portion of 50 a rail 1 of standard form having a base or flange 2 resting upon a tie plate 3. The plate 3 is in turn secured to an underlying tie 4 by screw spikes 5 of conventional form, the heads of which bear upon flat bosses 6. 55 However, the particular means for fastening the tie plate 3 to the underlying tie 4 does not constitute a part of our invention, and may obviously be varied to suit different conditions. 60

The tie plate 3 is formed with upstanding ribs 7, between which the rail base 2 is accommodated, and which serve as stops preventing lateral movement of the rail. Adjacent to the upstanding ribs 7 a slot 8 is formed at each side of the tie plate 3. The slot 8 is rectangular in shape at the top surface of the tie plate, as indicated at 9, and the walls of the slots are offset to afford shoulders, as indicated at 10, at the base of the slots. Beneath the shoulder 10 each slot is expanded to arcuate form, as indicated at 11 in Fig. IV. Within the rear wall 12 of each slot, a semi-circular recess 13 is formed, the recess preferably extending from the top 70 of the plate to the base thereof. 75

The rail retaining keys 14, 14a are made from a flat bar of resilient material and of uniform thickness, and are sharply bent at their end portions 15 to form horizontal legs 16, which are adapted to engage the tie plate 3 beneath the shoulders 10. The other end portions 17, 17a of the retaining keys 14, 14a, when the keys are assembled, project above the rail base 2, either in contact with the rail base, as shown at the left hand of Fig. II, to resist vertical movement of the rail with respect to the tie plate 3, or clear of the rail base and resting on a rib 7, as shown at the right hand of Fig. II, to serve as a stop limit- 85 90

ing vertical movement of the rail to a predetermined distance. While for the purpose of illustrating alternative arrangements, the key 14 shown at the right hand of the figure 5 is formed to assume one position with relation to the rail, whereas the key 14a shown at the left hand is formed to assume a different position, it will be understood that in the ordinary practice of the invention, the 10 same condition will exist at both sides of the rail.

To apply a retaining key, considering for example the key 14 shown at the right hand of the drawing, to a tie plate 3, the key is 15 inserted within the slot 8 with its end portions 15, 17 extending in a longitudinal direction, as indicated by the dot-and-dash lines in Fig. I. In this position, the leg 16 at the end 15 of the key fits within the rectangular 20 opening 9 at the top of the slot 8, permitting the key to drop downward until the leg 16 engages or approaches the top of the tie 4 at the underside of the tie plate 3. Thereupon the spring key 14 is turned through an 25 angle of 90° until it assumes the position shown in full lines. Incident to the turning of the key 14, the bent leg 16 is engaged beneath the shoulder 10. When the key 14 has reached its ultimate position transverse 30 to the rail 1, a projection 18 at the back of the key catches within the recess 13, as shown in Fig. IV, and opposes further turning of the key. At the same time, the end portion 17 of the retaining key 14 bears upon the 35 rib 7 with pressure engagement and projects above the rail base 2, the key being offset at 19, whereby the end portion 17 is at a predetermined clearance from the rail base.

The manner of applying the key 14a, 40 shown at the left hand of Figs. I and II, is similar to that described above, except that its inner end portion 17a is maintained in pressure engagement with the rail base 2, and the retaining key is out of contact with the 45 rib 7.

When so applied to the tie plate 3, the retaining keys 14, 14a will not be dislodged incident to the normal vibration or movement of the rail, for the forces exerted thereby, and 50 which tend primarily to lift the ends 17, 17a of the keys, rather than to turn the same, are adequately resisted by the locking engagement of the projections 18 within the recesses 13 at the rear walls 12 of the slots 8. To re- 55 move the retaining key 14, 14a, it is merely necessary to strike the key with a blow tending to free the projection 18 from its recess 13, and thereafter to turn the key to a position parallel to the rail 1 and to raise it clear 60 of the tie plate 3.

From the above description it will be noted that the retaining keys and tie plates of this invention are of simple and inexpensive manufacture and are readily assembled and 65 disassembled. Under certain conditions it

may be desirable to apply the retaining keys with their inner ends in pressure engagement with the rails, in which case they operate as rail fasteners, preventing or resisting any movement between the rails and tie plates, and under other conditions it may be found desirable to utilize the retaining keys as stops, not in actual contact with a rail, but limiting the extent of its vertical movement.

While we have described one example of the practice of our invention, with reference to a particular form of retaining key and tie plate, it will be apparent that various changes may be made in the shape of these parts as herein described, without departing from the spirit of our invention which contemplates a variety of forms for these parts.

Having thus described our invention, we claim:

1. In combination, a rail, a tie plate having a slot therethrough, the walls of said slot being offset to afford a shoulder at the base thereof, and a resilient retaining key having a bent end portion adapted to be passed through said slot and then turned to engage the tie plate beneath said shoulder and having the other end portion projecting above the base of the rail.

2. In combination, a rail, a tie plate having a slot therethrough, the walls of said slot being offset to afford a shoulder at the base thereof, and said walls having a recess therein, and a resilient retaining key having a bent end portion with a projection thereon, said end portion being adapted to be passed through said slot and then turned to engage the tie plate beneath said shoulder with said projection catching in said recess, and having the other end portion projecting above the base of the rail.

3. In combination, a rail, a tie plate having a slot therethrough, the walls of said slot being offset to afford a shoulder at the base thereof, and a resilient retaining key having a sharply bent end portion engaging the tie plate beneath said shoulder and having the other end portion projecting transversely above the base of the rail, said slot being so formed as to require the key to be inserted at an angle from said transverse position and then turned to said position.

4. In combination, a rail, a tie plate having a slot therethrough, the walls of said slot being offset to afford a shoulder at the base thereof, and a resilient retaining key having a sharply bent end portion adapted to be passed through said slot and turned therein to engage the tie plate beneath said shoulder and having the other end portion in pressure engagement with the rail base.

5. In combination, a rail, a tie plate having a rib thereon and a slot therethrough adjacent to said rib, the walls of said slot being offset to afford a shoulder at the base thereof, and a resilient retaining key having

a sharply bent end portion adapted to be passed through said slot and turned therein to engage the tie plate beneath said shoulder and having the other end bearing on said 5 tie plate rib and projecting over the rail base clear therefrom.

In testimony whereof, we have hereunto signed our names at Philadelphia, Pennsylvania, this 6th day of November, 1931.

10 ROBERT FARIES.
